Primary Examiner — Susan Moon Lee(57) **CLAIM**

The ornamental design for a scanner docking station, as shown and described.

DESCRIPTION

FIG. 1 is a front perspective view of a scanner docking station showing our new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view of the scanner docking station; and,

FIG. 9 is a front perspective view of the scanner docking station with a handheld scanner docked thereon.

Broken lines and portions contained within broken lines are not claimed.

1 Claim, 9 Drawing Sheets# US D678,889 S
